UNITED STATES PATENT OFFICE.

FREDERICK A. BALLOU AND CHARLES A. BURDETT, OF PROVIDENCE,
RHODE ISLAND; SAID BURDETT ASSIGNOR TO SAID BALLOU.

GEM-SETTING.

SPECIFICATION forming part of Letters Patent No. 634,567, dated October 10, 1899.

Application filed April 27, 1899. Serial No. 714,626. (No model.)

To all whom it may concern:

Be it known that we, FREDERICK A. BALLOU and CHARLES A. BURDETT, citizens of the United States, residing at Providence, in the county of Providence and State of Rhode Island, have invented certain new and useful Improvements in Gem-Settings, of which the following is a specification, reference being had therein to the accompanying drawings.

10 Like letters indicate like parts.

Figure 1 is an enlarged view, in side elevation, of a wire for the manufacture of a stick-pin to be provided with our improved gem-setting. Fig. 2 is an enlarged view, in side elevation, of said wire after one end thereof has been reduced in diameter and grooved. Fig. 3 is an enlarged view, in side elevation, showing said reduced and grooved end of the wire bent to form a circular loop, within which 20 loop the gem is set. Fig. 4 is the same as Fig. 3, except that it shows a collar or tube put on over the parts of the wire which are in contiguity. Fig. 5 is an enlarged view of the gem in side elevation and of the gem-setting in cross-section on line *v v* of Fig. 3. Fig. 6 is a plan view of the finished stick-pin provided with a gem and our improved gem-setting.

Our invention relates to gem-settings for 30 pins and similar articles; and it consists of a wire having one end pointed and the opposite end reduced in diameter and grooved on one side and bent to form an integral loop, the extreme portion of said reduced end extending 35 as a lap straight along and against the pin, and a collar surrounding the pin and said lapped portion and swaged so as to have its exterior surface continuous with the exposed surface of the pin.

40 In Fig. 1 we show a wire blank *A'*, which is to be made up into a stick-pin, such as is shown in Fig. 6. The wire *A'* is reduced at and near one end thereof, as seen at *g* in Fig. 2, and a groove is rolled in or burred, as indicated by the dotted line in said figure. The 45 end *g* is bent into the circular loop shown in Fig. 3 to inclose the gem *B'*, and the extremity of said part *g* is lapped over and lies straight

along and against the wire *A'*, as seen in said figure at *h*. A short tube, collar, or section 50 of hollow wire *C*, having an inner diameter sufficiently large to inclose the wire *A'* and said straight portion *h* of the reduced wire *g*, is slipped on over the wire *A'* and straight lap *h* until its forward end abuts the loop *g*, as 55 shown in Fig. 4. The gem *B'* is thus secured in place within the grooves of the loop *g*, as seen in Fig. 5, and by a swaging operation in said reducing-machine the collar *C*, wire *A'*, and lap *h* are all hammered down to the shape 60 illustrated in Fig. 6.

In the methods of manufacture heretofore employed in making such pins solder has generally been used, thereby softening the stock and impairing the temper thereof. As we 65 entirely dispense with the use of solder in the manufacture of these pins, the temper, stiffness, and strength of the pins are not impaired, but rather increased. This is especially important in the manufacture of gold- 70 plated goods.

The setting produced as above described is smooth and has no projections or points, and therefore wears well, does not catch into the fabric, and holds the gem securely in position. 75

We claim as a novel and useful invention and desire to secure by Letters Patent—

In combination with a gem, a pin having one end pointed and the other end reduced 80 in diameter, and grooved on one side and bent to form an integral loop with said groove on its inner surface, the extreme portion of said reduced end extending as a lap straight along and in contact with the pin, a collar, surrounding the pin and lapped portion thereof 85 and swaged so as to have its exterior surfaces continuous with the surface of the pin outside of said collar, substantially as specified.

In testimony whereof we affix our signatures in presence of two witnesses.

FREDERICK A. BALLOU.
CHARLES A. BURDETT.
